DESIGN FOR A SPECTACLE FRAME

Alexander Kono, Flushing, N. Y., assignor to The Kono Manufacturing Company, Woodside, N. Y., a firm composed of Alexander Kono, Blanche Kono, and Florence Smith

Application May 1, 1946, Serial No. 129,201

Term of patent 14 years

(Cl. D57—1)

To all whom it may concern:

Be it known that I, Alexander Kono, a citizen of the United States of America and resident of Flushing, county of Queens, and State of New York, have invented a new, original, and ornamental Design for a Spectacle Frame, of which the following is a specification, reference being had to the accompanying drawing, forming part thereof, in which

Fig. 1 is a front elevational view of a spectacle frame, and

Fig. 2 is a top plan view therof, showing my new design, the essential feature of which is the specific configuration of the frame.

I claim:

The ornamental design for a spectacle frame, as shown and described.

ALEXANDER KONO.
